2,3
VARIABLE'S
Bewley W. Grim
Application July 1,
5 Claims.

My invention relates to Diesel engines and other internal combustion engines of the fuel injection type, and has among its objects and advantages the provision of an improved fuel injection pump embodying a novel cam means for imparting a variable stroke to the pump plunger. Said means imparting a desirable change in phase relation of the camming to the crankshaft of the internal combustion engine.

In the accompanying drawing:

Figure 1 is an end view, and

Figure 2 is a sectional view along the line 2—2 of Figure 1.

In the embodiment of the invention selected for illustration, the pump 10 comprises a base 12 having side walls 14 interconnected by a top wall 16. Upon the wall 16 is mounted a pump body 18 having a bore 20 within which is slidably mounted the pump plunger 22.

A valve controlled fluid inlet conduit 24 has communication with the bore 20. A similar conduit 26 is provided for the fuel forced from the bore 20. A stem 28 is attached to the plunger 22 and is provided with a head 30 engageable by a cam 32. Between the head 30 and a plate 34 attached to the body 18 is interposed a compression spring 36 for yieldingly urging the head 30 against the cam 32. The plate 34 is in the nature of a split washer which slidably guides the stem 28 and acts as a stop for the plunger 22, so that the plunger stroke will always begin at the same point.

The cam 32 is fixedly related to a driven gear 36 meshing with a drive gear 38. The gear 38 is fixed to a drive shaft 40, and the driven gear 36 may be oscillated about the axis of the drive gear 38 for adjusting the cam 32 to different positions for varying the plunger stroke and advancing or retarding the cam action. Links 42 are pivotally connected with the shaft 40 and with a shaft 44 to which the driven gear 36 and the cam 32 are fixedly connected. The links guide the gear 36 for movement in a path concentrically of the gear 38.

Means for adjusting the cam 32 comprises a link 46 pivotally connected with the shaft 44 and with a body 48. This body is provided with a dovetail 50 slidably guided between dovetail flanges 52 on the base 12. An adjusting screw 54 has a swivel connection with the body 48, as at 56, and is threaded through a lug 58 fixed to the base 12. This screw parallels the base 12, while the link 46 may be pivoted to different angular positions from its coaxial position with the plunger 22, to raise and lower the cam 30,

Herbaceous plants, especially in the wetter areas, are often of great value as a source of food for the birds, and the presence of such plants in the garden is a great help to the bird-life. The following are some of the more common plants which are especially valuable to the birds:

1.103-38) thereby varying the stroke of the plunger and the phase cam.

The drive gear 38 is rotated counterclockwise when viewing Figure 2. The drawing illustrates a pump wherein the plunger has a maximum stroke of one-half inch, and in which the gears 36 and 38 have diameters of two inches.

The mounting of the driven gear and the cam is arranged to move in relation to the plunger 22, either toward the plunger or away from it, in an arc concentrically of the drive gear 38. The bottom of the plunger stroke is always the dead part of the cam in full load position. Pulling the cam 32 downwardly shortens the plunger stroke. When the driven gear 36 is in the top position for full load, the angle formed by the cam and its shaft support is 90° for a one-half inch stroke. To retard the engine to three-quarter load, the cam is dropped one-quarter of the 20 distance which then permits three-quarters of a plunger stroke, in addition to advancing the injection, since the angle of the cam and its support now approximates 86° . In dropping the cam to a zero load position, the cam angle is 76° . 25 This results in a phase change in advance of 90° to 76° . It is well known that the injection must be advanced as the engine speed is lowered. My invention may be constructed so that the angle of the cam and its support will give the required 30 change. The angle is altered by changing the drive and driven gears to greater or lesser diameters. The plunger is spring loaded and the bottom of its stroke is the dead side of the cam in the fully advanced position.

35 This pump is of exceedingly simple and durable construction, in addition to being easily operated. The large camming surface increases its resistance to wear. Positive control of injection timing or phase change is automatically provided.

40 This means of changing timing relations is adaptable to many mechanisms, such as the timing of spark ignition systems etc., wherever such action is desirable. The screw 54 may be manually actuated or connected with a suitable governor.

45

Without further elaboration, the foregoing will so fully explain my invention, that others may, by applying current knowledge, readily adapt the same for use under various conditions of service.

50 I claim:

1. A fuel injection pump comprising a body having a bore and an outlet communicating therewith, a rotary cam, a plunger operating in said bore to force fuel through said outlet and 55 yieldingly biased against said cam, a rotary

drive means, a rotary driven means operatively engaging said drive means and fixed to said cam, and means for oscillating said driven means about the axis of said drive means to vary the stroke of said plunger.

2. A fuel injection pump comprising a body having a bore and an outlet communicating therewith, a rotary cam, a plunger operating in said bore to force fuel through said outlet and yieldingly biased against said cam, a rotary drive means, a rotary driven means operatively engaging said drive means and fixed to said cam, and means for oscillating said driven means about the axis of said drive means to change the phase of said cam with respect to said drive means.

3. A fuel injection pump comprising a body having a bore and an outlet communicating therewith, a rotary cam, a plunger operating in said bore to force fuel through said outlet and yieldingly biased against said cam, a rotary drive means, a rotary driven means operatively engaging said drive means and fixed to said cam, said drive means and said driven means each comprising a gear, a link means supporting said driven gear for oscillation about the axis of the drive gear, and a screw actuated means for pivoting said link means about the axis of said drive means for changing the phase of said cam with respect to said drive gear.

4. A fuel injection pump comprising a body having a bore and an outlet communicating therewith, a rotary cam, a plunger operating in said bore to force fuel through said outlet and yieldingly biased against said cam, a rotary drive means, a rotary driven means operatively engaging said drive means and fixed to said cam, said drive means and said driven means each comprising a gear, a rotary shaft having the driven gear and said cam fixed thereto, a link means pivotally connected with said shaft and mounted for pivotal movement about the axis of said drive means, a second link pivotally connected with said shaft, a body mounted for sliding movement in a path at right angles to said plunger, said second link being pivotally connected with said body, and screw means for adjusting said body to oscillate said driven gear, the cam and said shaft about the axis of the drive gear to vary the stroke of said plunger.

5. In a pump having a reciprocating plunger, a rotary drive means, a cam for actuating said plunger, a driven means fixed to said cam and operatively engaging said drive means, and a support for said driven means and said cam mounted for oscillation about the axis of said drive means to oscillate the driven means and said cam about said drive means to vary the timing of the plunger.
